(57) **CLAIM**

The ornamental design for a stackable slider toy block, as shown and described.

DESCRIPTION

FIG. 1 is a top, left, front perspective view of the stackable slider toy block of my design;

FIG. 2 is a bottom, rear, right perspective view thereof;

FIG. 3 is a left elevation view thereof;

FIG. 4 is a right elevation view thereof;

FIG. 5 is a front elevation view thereof;

FIG. 6 is a back elevation view thereof;

FIG. 7 is a top plan view thereof;

FIG. 8 is a bottom plan view thereof;

FIG. 9 is an environmental elevation view of the stackable toy block in a stacked condition;

FIG. 10 is an environmental top perspective view of the stackable toy block in a stacked condition;

FIG. 11 is an environmental top perspective view of the stackable toy block in a stacked condition; and,

FIG. 12 is an environmental top perspective view of the stackable toy block in a stacked condition.

The broken lines shown represent unclaimed subject matter and form no part of the claimed design.
